UNITED STATES PATENT OFFICE.

ERNEST R. PHILIP, OF ATLANTA, GEORGIA, ASSIGNOR TO AMERICAN CAN COMPANY, OF NEW YORK, N. Y., A CORPORATION OF NEW JERSEY.

TURPENTINE-COLLECTING APRON AND RECEPTACLE.

No. 913,845.

Specification of Letters Patent.

Patented March 2, 1909.

Application filed November 29, 1907. Serial No. 101,846.

To all whom it may concern:

Be it known that I, ERNEST R. PHILIP, a citizen of the United States, residing in Atlanta, in the county of Fulton and State of Georgia, have invented a new and useful Improvement in Turpentine-Collecting Aprons and Receptacles, of which the following is a specification.

My invention relates to improvements in sheet metal sap collecting aprons and receptacles.

The object of my invention is to provide a sheet metal sap collecting apron and receptacle of a strong, simple, efficient and durable construction, capable of being cheaply manufactured, and which will serve to protect the turpentine or other sap collected in the vessel from dirt or other foreign matter falling into the receptacle.

20 My invention consists in a sheet metal collecting apron for turpentine or other sap, furnished with an extension to cover the receptacle, into which the turpentine or other sap is delivered by the apron.

25 It further consists in a sap collecting apron furnished with a cover extension for the vessel, and provided with an opening through which the turpentine or other sap may flow into the collecting vessel or receptacle.

30 It further consists in a sap collecting apron having a cover extension for the vessel and provided with means for removably attaching the collecting vessel or receptacle thereto.

35 It further consists in combination with the collecting apron and cover extension thereof of a detachable collecting vessel and means for locking the collecting vessel in position on the collecting apron or its extension to prevent the collecting vessel from being disturbed or accidentally disconnected by winds or cattle.

40 It further consists in the novel construction of parts and devices and in the novel combinations of parts and devices herein shown and described and more particularly specified in the claims.

45 In the accompanying drawing forming a part of this specification, Figure 1 is a front elevation of a turpentine or other sap collecting apron and cup or receptacle embodying my invention. Fig. 2 is a central vertical section on line 2—2 of Fig. 1. Fig. 3 is a section on line 3—3 of Fig. 2. Fig. 4 is a detail plan view of the collecting cup or receptacle. Fig. 5 is a detail section on line

5—5 of Fig. 1. Fig. 6 is a perspective view illustrating a modification wherein a rectangular one piece cup or receptacle is employed instead of a round cup as illustrated in the other figures.

60 In the drawing, A represents a turpentine or other sap bearing tree, B the sheet metal apron inserted in the cut a of the tree, B¹ the cover extension thereof for the cup or receptacle and D the collecting cup or receptacle.

65 The sap collecting apron B is of sheet metal and preferably furnished with a concavely curved upper edge b. It is also provided with converging offsets b¹ leading from the upper corners of the apron to the discharge opening b² through which the turpentine or other sap flows into the collecting receptacle or cup D. These converging offsets or guides b¹ also serve to stiffen the apron as well as to direct the sap or gum into the receptacle.

70 The cover extension B¹ is preferably made integral with the apron B and it preferably projects at an inclination to the apron B, as ordinarily, it is desirable that the top of the receptacle D should be more nearly horizontal than the apron B. The opening b² at the lower end of the apron through which the sap or gum flows into the vessel D is preferably formed by slitting the apron and turning up 75 a lip b³ at the slit portion. The cover extension B¹ of the apron B is preferably furnished with one or more raised beads b⁴ to strengthen and stiffen the same.

75 The cup or receptacle D may be of any suitable shape or construction. Instead of supporting the cup or receptacle D by means of a nail driven in the tree and providing one of the upright walls of the receptacle with a hole near its upper edge to hook over the nail, I prefer to provide the cover extension of the apron and the cup D with interengaging supporting means for the cup, the same preferably consisting in curved flanges or guides b⁵ on the parallel side edges of the 80 cover extension engaging corresponding side guides, flanges or shoulders d at the top of the cup or receptacle D. The interengaging guides b⁵ on the apron extension and d on the receptacle not only afford a convenient 85 means for suspending or supporting the receptacle, but also serve to hold the cover extension close upon or over the top of the receptacle. The cover extension B¹ of the apron is also preferably provided with a 90

curved flange or lock b^6 at its front or outer edge which embraces or engages the wired or shouldered upper edge d^4 at the front of the receptacle D and thus locks the receptacle in position on the apron and its extension so that it cannot be accidentally dislodged by wind or by cattle or other animals rubbing against it.

To remove the detachable collecting receptacle D from the collecting apron and its cover extension to empty the turpentine or other gum therein, the receptacle is first pushed slightly towards the tree to disengage the locking lip b^6 from the external shoulder 10 or wire d^4 at the upper edge of the vessel and then the apron extension B^1 is sprung slightly upward at its front edge so that the lock b^6 will pass the top edge of the vessel and then the vessel D is slipped outward from 15 the tree and removed. To replace the receptacle D, the same is simply slipped under the cover extension of the apron, the cup as it is slipped home causing the cover extension of the apron to spring slightly upward 20 as the locking lip b^6 snaps over the front outer rim of the vessel.

In Fig. 6 my invention is illustrated as applied to a one piece folded rectangular cup or vessel, such, for example as is illustrated 30 in my Patent No. 858,305 of June 25, 1907. The construction and operation of the parts in this figure are the same as above described, excepting that the cup D is of a rectangular one piece folded construction instead of a round, pieced form as shown in 35 Figs. 1, 2, 3 and 4.

I claim:

1. The combination of a sheet metal collecting apron for turpentine or other sap, 40 having an opening for the discharge of the sap and converging offsets for directing the turpentine or sap to such opening, and provided with a cover extension for the collecting vessel furnished with guides for engaging 45 and supporting the vessel, and a sap collecting vessel provided with side guides engaging the guides on said cover extension, substantially as specified.

2. The combination of a sheet metal collecting apron for turpentine or other sap, 50 having an opening for the discharge of the sap and converging offsets for directing the turpentine or sap to such opening, and provided with a cover extension for the collecting vessel furnished with guides for engaging 55 and supporting the vessel, and a sap collecting vessel provided with side guides engaging the guides on said cover extension, said cover extension having also at its outer edge 60 a locking lip to lock the vessel in position, substantially as specified.

3. A substantially flat sheet metal sap collecting apron, having an upper edge adapted 65 for insertion in a tree incision and converging guides to direct the sap to an opening, and

provided with an integral cover extension adapted to cover a sap receptacle, and having an opening for a sap to flow through into the sap receptacle beneath said cover extension, substantially as specified.

4. A substantially flat sheet metal sap collecting apron, having an upper edge adapted for insertion in a tree incision and converging guides to direct the sap to an opening, and provided with an integral cover extension adapted to cover a sap receptacle, and having an opening for a sap to flow through into the sap receptacle beneath said cover extension, said cover extension projecting at an angle to the apron proper, substantially as 70 specified.

5. A substantially flat sheet metal sap collecting apron having an upper edge adapted for insertion in a tree incision, and converging guides to direct the sap to an opening, and an opening through which the sap is directed by said guides into a receptacle beneath the cover extension, and provided with an integral cover extension for a sap receptacle, said cover extension projecting at an angle to the apron proper, and said cover extension having means for detachably securing the receptacle thereto, in combination with a receptacle substantially as 85 specified.

6. The combination of a substantially flat sheet metal sap collecting apron having an upper tree inserting edge and converging guides for the sap, with a covering piece projecting rigidly from said apron, and a 100 collecting vessel removably supported beneath the covering piece, there being an opening at the lower end of the apron for the sap to flow through into the vessel, substantially as specified.

7. The combination of a substantially flat sheet metal sap collecting apron having an upper tree inserting edge and converging guides for the sap, with a covering piece projecting rigidly from said apron, and a 110 collecting vessel removably supported beneath the covering piece, there being an opening at the lower end of the apron for the sap to flow through into the vessel, said covering piece and vessel having interengaging 115 supporting devices for detachably connecting the vessel to the covering piece, substantially as specified.

8. The combination of a substantially flat sheet metal sap collecting apron having an upper tree inserting edge and converging guides for the sap, with a covering piece projecting rigidly from said apron, and a collecting vessel removably supported beneath the covering piece, there being an 120 opening at the lower end of the apron for the sap to flow through into the vessel, said covering piece and vessel having interengaging 125 supporting devices for detachably connecting the vessel to the covering piece, and

- means for locking the collecting vessel in position under the covering piece, substantially as specified.
9. A sap collector comprising a flat metal 5 apron having its upper edge adapted to fit an incision in a tree, and provided with guiding means for the sap, a cover extension integral with the apron provided with receptacle supporting means and a receptacle, said 10 collector being provided with an opening to direct the sap into said receptacle.
10. A substantially flat sheet metal sap collecting apron, having at its upper end a transversely extending edge adapted for insertion in the tree incision, and provided 15 with guides for the sap, and an opening at its lower portion for the sap to flow through into a vessel beneath the cover extension, and furnished with a cover extension having 20 integral supporting devices for engagement with a vessel to removably support the vessel from the apron through said cover extension, substantially as specified.
11. A flexible sheet metal sap collecting 25 apron of substantially flat form provided with an upper transverse edge adapted for insertion in a tree incision, guides for directing the sap, an integral cover extension for a collecting vessel and an opening for the 30 sap to flow through into the vessel beneath said cover extension and a collecting vessel supported beneath said cover extension.
12. A flexible sheet metal sap collecting 35 apron having an upper transverse edge adapted for inserting in the tree incision, and guides for directing the sap and provided with an integral cover extension for a collecting 40 vessel and an opening therein for the sap to flow through into the vessel beneath the covering piece, and a collecting vessel supported beneath said cover extension, said cover extension and said vessel having interengaging supporting devices for detachably connecting the vessel with the cover extension of the apron, substantially as specified.
13. A sap collecting apron having an integral cover extension for a collecting vessel and an opening therein for the sap to flow through into the vessel beneath the covering 50 piece, and a collecting vessel supported beneath said cover extension, said cover extension and said vessel having interengaging supporting devices for detachably supporting the vessel beneath the cover extension of the apron, and said cover extension of the apron having a locking lip engaging the upper rim of the vessel to lock the vessel in position beneath the apron, substantially as specified.
14. The combination with a flexible sheet 60 metal sap collecting apron of substantially flat form and having an upper transverse edge adapted for inserting in the tree incision, and guides for directing the sap and provided with a discharge opening and pro-
- vided with an integral cover extension furnished at its ends with curved flanges adapted to engage with the rim of a collecting vessel, substantially as specified.
15. The combination with a flexible sheet 70 metal sap collecting apron of substantially flat form and having an upper transverse edge for inserting in the tree incision, and guides for directing the sap and provided with a discharge opening and provided with 75 an integral cover extension furnished at its ends with guides for engagement with the rim of a collecting vessel, and a collecting vessel having supporting guides at its rim interfitting with the guides on the cover extension of the apron, substantially as specified.
16. The combination with a sap collecting 80 apron having a discharge opening and provided with an integral cover extension furnished at its ends with guides for engagement with the rim of a collecting vessel, and a collecting vessel having supporting guides at its rim interfitting with the guides on the cover extension of the apron, and a locking 85 lip on the cover extension of the apron adapted to engage the rim of the vessel at the front thereof to lock it in position, substantially as specified.
17. The combination with a sap collecting 90 apron having a discharge opening and provided with an integral cover extension furnished at its ends with guides for engagement with the rim of a collecting vessel, and a collecting vessel having supporting guides at 95 its rim interfitting with the guides on the cover extension of the apron, and a locking lip on the cover extension of the apron adapted to engage the rim of the vessel at the front thereof to lock it in position, said cover extension of the apron being adapted to be sprung upward in removing and replacing the vessel, substantially as specified.
18. A substantially flat sheet metal one-piece sap collecting apron and cover for a 100 collecting vessel, provided at its upper end with a transversely extending edge adapted for insertion in a tree incision, and furnished at its upper or apron portion with converging sap guides, the device being provided 105 with an opening so located as to direct the sap into a collecting vessel.
19. A substantially flat sheet metal one-piece sap collecting apron and cover for a 110 collecting vessel, provided at its upper end with a transversely extending edge adapted for insertion in a tree incision, and furnished at its upper or apron portion with converging guides to direct the sap, and furnished near the lower end of said apron portion with 115 an opening for the sap to flow through into a receptacle beneath the cover portion, said cover or extension portion extending at an angle from the apron portion, substantially as specified.

20. A substantially flat sheet metal one-piece sap collecting apron and cover for a collecting vessel, provided at its upper end with a transversely extending edge adapted for insertion in a tree incision, and furnished at its upper or apron portion with converging guides to direct the sap, and furnished near the lower end of said apron portion with an opening for the sap to flow through into a receptacle beneath the cover portion, said cover portion being furnished with integral means for supporting the collecting vessel therefrom, substantially as specified.

21. A sheet metal sap collecting apron, having at its upper end a transversely extending edge adapted for insertion in a tree incision and furnished with converging guides to direct the sap, and an opening for the sap to flow through at its lower end into a vessel beneath the cover extension of said apron, said apron being provided with an integral cover extension projecting from its lower end and provided with means for detachably connecting a collecting vessel to said

cover extension and supporting it therefrom, substantially as specified.

22. A sheet metal sap collecting apron, having at its upper end a transversely extending edge adapted for insertion in a tree incision and furnished with converging guides to direct the sap, and an opening for the sap to flow through at its lower end into a vessel beneath the cover extension of said apron, said apron being provided with an integral cover extension projecting from its lower end and provided with means for detachably connecting a collecting vessel to said cover extension and supporting it therefrom; in combination with a collecting vessel having at its upper end supporting devices for removable engagement with said supporting means on said cover extension, substantially as specified.

ERNEST R. PHILIP.
